POWER PLANT AND ENGINE ARRANGEMENT

Anker K. Antonsen, Cedar Falls, Iowa, assignor
to Fairbanks, Morse & Co., Chicago, Ill., a cor-
poration of Illinois

Application December 30, 1938, Serial No. 248,497

2 Claims. (Cl. 290—1)

This invention relates to improvements in power plant and engine arrangement, and more particularly to an improved disposition of operating engine accessories of engines of internal combustion type, in relation to direct-connected power-consuming units, for example, a generator closely and directly coupled to the engine by which it is driven.

In present day marine and railway installations, and in the case of many stationary installations, it is highly advantageous so to arrange an engine in relation to a power-consuming unit driven thereby, and to arrange the operating engine accessories, such as pumps, blowers and other power-requiring adjunctives of the engine proper, such as to require a minimum of space about the engine, and so as most economically to utilize the usually limited head room above the engine, as well as to minimize the overall length of the power plant. It is, in many cases, of equal importance to economize on requirement of overall width of the power plant, and particularly that of the engine proper, so as to provide head room and easy access for an operator for routine attention to each side of the engine, and for access to controls and to all operating portions of the plant. The present invention has as its major objective, the attainment of the foregoing advantages in a measure considerably improved over that heretofore attained in direct-connected installations of comparable type. The present invention is particularly applicable to vertical multi-cylinder internal combustion engines, and in the particular example selected for present disclosure, is shown as applied to a two-cycle engine of this type, employing a blower as a source of scavenging air. The reference in the specification and claims to a vertical engine, is not intended to exclude V type designs, but is utilized to embrace all of the several types wherein the height of the engine proper is one of its predominant dimensions.

Another important object of the invention may be stated as attained in an improved location and mounting of a blower on an engine of vertical type, and such that the blower is easily removable, and upon removal, permits full access to, and easy removal and replacement of the direct-connected power-consuming unit, such as a generator.

Another object akin to those heretofore stated, is attained in an improved flange mounting at the load end of an engine frame structure, such that, when the blower is removed, full vertical

clearance is provided to enable lifting or lowering the generator or other power-consuming unit, so as to permit it to swing clear of the end of the engine frame and yet, when the parts are operatively assembled, to utilize to fullest advantage, the space at the end of the power take-off end of the engine.

Yet another object may be stated as an improved disposition and arrangement of operating engine accessory, such as to keep both sides of the engine free and clear for purposes of service and access.

The foregoing and numerous other objects and advantages of the invention will appear as the description proceeds, when considered in connection with the accompanying drawing, herein-after referred to.

The invention in its broader aspects is applicable to an engine designed and arranged for direct-connection to any of the usual or suitable power-consuming units such as an electric generator, a mechanical or hydraulic reduction gear, hydraulic coupling, or any other rotary mechanism of a type which may be connected directly to a crankshaft extension or other power take-off shaft of the engine, and which will usually be coupled closely thereto. Accordingly, the unit described as a power-consuming unit, although illustrated and exemplified as an electric generator, should be taken to include any rotary mechanism which may be employed as the driven apparatus in a direct-connected power plant. Similarly, although the operating engine accessory of the presently selected embodiment of the invention, consists of a scavenging air blower, it may likewise consist of any of the operative adjuncts necessary to the operation of the engine and forming a part thereof.

In the drawing, Fig. 1 is a top or plan elevation of an engine constructed in accordance with the present improvements, together with a direct-connected electric generator; Fig. 2 is a side elevation of the power plant shown by Fig. 1, and Fig. 3 is a fragmentary vertical sectional elevation, somewhat enlarged, of the assembly shown by Figs. 1 and 2 and as viewed along line 3—3 of Fig. 1.

Referring by characters of reference to the drawing, a generator 5 is shown only in outline, as the parts and internal construction thereof are not material to the present improvements or design. A generator shaft 6 is shown as operatively connected through a balancer and coupling device 7 to an extended end portion 8 of the lower crankshaft 9 of the engine. The en-

gine includes a sub-base and case portion 10, a frame structure thereabove, indicated generally at 11, an exhaust belt or deck including a manifold 12 provided with a connection 13 for the 5 exhaust piping. The engine controls are exemplified in the present disclosure by a lever 15.

The frame 11 is provided, by preference, with a frame extension 16 at its load end, this extension being provided with flanges such as 17 10 equipped with a plurality of holding screws 18 for the detachable securement of the casing 19 of a scavenging air blower indicated generally at 20. The blower is of a modified Roots type, including a pair of shafts 21 and 22, with corresponding 15 blower rotor elements 23 and 24 secured respectively to the shafts 21 and 22. An air inlet is provided to the blower 20 through an inlet port or opening 30, and the air is discharged through a connection (not shown) into the frame of the 20 engine, to a space about the cylinders 31 of the engine, one of which is shown by Fig. 3, whence the air is available for scavenging purposes as through the ports 32, as from an air belt, chamber or manifold 33. The details of the air 25 passages into and internally of the frame of the engine form of themselves no part of the present invention but are described and claimed in a copending application of Hans Davids, et al., filed August 28, 1939, and bearing Serial No. 292,231; 30 also a co-pending application of James W. Owens, filed August 28, 1939, and bearing Serial No. 292,230.

The engine disclosed is of two-cycle opposed piston type, embodying a plurality of the cylinders 31. The cylinder proper is provided by a removable liner assembly, constituting the subject matter of a copending application of Anker K. Antonsen et al., filed December 30, 1938, and bearing Serial No. 248,434. Each cylinder is 40 provided with a pair of pistons 34 and 35 connected respectively, through rods 36 and 37 to the lower and upper crankshafts of the engine, the lower thereof being indicated at 9 and the upper crankshaft at 49. These crankshafts are 45 operatively connected in timed relation through the provision of a sprocket 41 on shaft 9, a corresponding sprocket 42 on shaft 40 and a silent chain 43 engaging the sprockets.

A power drive for the operating engine accessory such as the blower 20, is shown as including 50 a gear 45 secured to an extension 46 of crankshaft 40. With gear 45 meshes a smaller gear 47 carried by the lower blower shaft 21; shaft 21 also carries a gear 48 which enmeshes with a 55 companion gear 49 on shaft 22. It will thus appear that through rotation of the shaft 40 the blower drive is effected through gears 45-47, and the two rotor shafts of the blower are revolved in the usual definite relation through gearing 48 and 49, the blower being driven at somewhat higher speed than the crankshafts due to the step-up relation provided by the larger gear 45 and smaller 47.

It will clearly appear from the drawing that 60 the zone of the detachable flange securement of the blower casing to the engine frame, as through flanges 17, is substantially in the same transverse plane as the inner end of the body of the generator 5. Thus when the blower is removed, 65 as may be easily done, the generator may be readily disconnected through the balancer and coupling device 7 and vertically hoisted or lowered into place for ease of assembly and removal.

It will have appeared that the location of one 70 of the larger operating engine accessories such

as the blower, at the load end of and in overhanging relation to the generator, serves to clear both sides of the engine so as to enable ready access to practically all operating parts thereof at all times, and to provide an increased width of 5 runway for the engine attendant at each side of the power plant.

The current design is preferably embodied in an arrangement of the overhanging blower such that the casing 19 does not extend appreciably 10 above the removable hood elements 50 which overlie the upper crankshaft, and hence does not, in spite of its end mounting, add anything to the head room requirement of the engine. Otherwise expressed, this operating engine adjunct 15 exemplified by the blower, utilizes only a space above the generator or similar unit, which would otherwise be waste space, and since it does not add to the overall width of the engine proper, being within the confines thereof, offers an especially 20 advantageous location in installations such as those in submarines, as well as in railway usage, and in fact in any arrangement where space about the power plant is at a premium.

Although the blower has been shown as arranged with its rotor axes, being those of shafts 21 and 22, in the same vertical plane as the shaft of generator 5, in case the generator frame is relatively higher, the blower may be mounted otherwise than as shown.

From the foregoing it will have appeared that the arrangement illustrated and described, fully attains each of the several objectives hereinabove expressed, as well as the other advantages appearing from the more detailed description of 35 the arrangement selected for disclosure.

Although the invention has been described by making rather specific reference to a selected embodiment thereof, it is to be understood that many changes may be made in the structure and arrangement of parts, without departing from the spirit and intended scope of the invention as defined by the claims hereunto appended.

I claim as my invention:

1. A direct-connected power plant including a 45 vertical multi-cylinder, two-cycle, opposed-piston engine having an upper crankshaft, a lower crankshaft, and a positive operative connection between said crankshafts, a generator closely coupled to the lower crankshaft, the engine including a frame structure provided with an extension on the upper portion of its generator-load end, said upper crankshaft projecting into said frame extension and having a gear element secured thereto, a Roots type blower detachably 50 carried by said frame extension and projecting in overhanging relation to the generator, the blower including a pair of gear-connected rotor shafts, one thereof projecting inwardly of said frame extension and having a pinion secured thereto, 55 operatively meshing with said engine crankshaft gear element, the other of said blower rotor shafts being substantially in axial alignment with the upper crankshaft of the engine, the zone of connection of the blower to the overhanging portion 60 of the engine frame being axially inward of the generator, whereby to provide for vertical clearance for lifting the generator or parts thereof vertically with respect to its mounting, upon removal of the blower.

2. A direct-connected power plant including a 65 vertical multi-cylinder, two-cycle, opposed-piston engine having an upper crankshaft, a lower crankshaft, and a positive, operative connection between said crankshafts, a generator closely 70

coupled to the lower crankshaft, the engine including a frame structure provided with an extension on the upper portion of its generator-load end, said upper crankshaft projecting into said frame extension and having a gear element operatively secured thereto, a Roots type blower detachably carried by said frame extension and projecting in overhanging relation to the generator, the blower including gear-connected upper and lower rotor shafts, the upper shaft thereof being substantially in axial alignment with the upper crankshaft of the engine, and the lower shaft of the blower projecting inwardly of said

engine frame extension and having a pinion secured thereto, operatively meshing with said crankshaft gear element, for driving the blower, said gear and pinion being relatively adapted for effecting a blower speed substantially greater than the engine speed, the zone of connection of the blower to the overhanging portion of the engine frame being axially inward of the generator, whereby to provide for vertical clearance for lifting the generator or parts thereof vertically with respect to its mounting, upon removal of the blower.
